No. 37,152.

Patented September 27, 1904.

UNITED STATES PATENT OFFICE.

AUGUST NEDERLAND, OF BROOKLYN, NEW YORK.

DESIGN FOR AN ADVERTISING-CARD.

SPECIFICATION forming part of Design No. 37,152, dated September 27, 1904.

Application filed August 5, 1904. Serial No. 219,670. Term of patent 7 years.

To all whom it may concern:

Be it known that I, AUGUST NEDERLAND, a citizen of the United States, residing at Brooklyn, in the county of Kings and State of New York, have invented a new, original, and ornamental Design for an Advertising-Card, of which the following is a specification.

The accompanying drawing represents the ornamental design.

What is claimed as new is—
The ornamental design for an advertising-card, as shown.

AUGUST NEDERLAND.
